CLAIM

The ornamental design for a laptop protection case set, as shown and described.

DESCRIPTION

FIG. 1 is a front, bottom and right side perspective view of a first component of a laptop protection case set showing my new design;

FIG. 2 is a rear, top perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front, bottom and right side perspective view of a second component of the laptop protection case set showing my new design;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a front, bottom and right side perspective view of the laptop protection case set.

The broken lines in the drawings depict portions of the laptop protection case set that form no part of the claimed design.
